UNITED STATES PATENT OFFICE.

JOSEPH R. SMITH, OF WATERBURY, CONN., ASSIGNOR TO WATERBURY
BUTTON COMPANY, OF SAME PLACE.

HAIR-PIN.

SPECIFICATION forming part of Letters Patent No. 225,430, dated March 9, 1880.

Application filed October 23, 1879.

To all whom it may concern:

Be it known that I, JOSEPH R. SMITH, of Waterbury, in the county of New Haven and State of Connecticut, have invented a new Improvement in Hair-Pins; and I do hereby declare the following, when taken in connection with the accompanying drawings and the letters of reference marked thereon, to be a full, clear, and exact description of the same, and which said drawings constitute part of this specification, and represent, in—

Figure 1, view of the pin complete; Fig. 2, vertical central section enlarged.

This invention relates to an improvement in that class of two or more pronged hair-pins which are provided with a head; and the invention consists in the peculiar construction of the head, as hereinafter described, and particularly recited in the claim.

The hair-pin proper is made from wire bent to form two prongs, *a a*, in substantially the usual manner. Over these prongs there is passed a cup-shaped or hemispherical disk, *b*, perforated, as at *c*, so that the two prongs of the pin may pass therethrough. Between the upper bend, *d*, of the pin and the bottom of the disk *b* a block, *e*, of any suitable material, is introduced to hold the bend above the sur-

face of the disk; then over the bend of the pin there is placed an inverted cup, *f*, (denoted in solid black, Fig. 2,) which closes down over the upper part of the lower disk, *b*, the two parts together forming substantially a spherical shape. The upper part or cap *f* bears upon the bend of the pin, so as to press it hard down upon the filling-block *e*, and thus hold the pin firmly to the head. This completes the construction.

The cap may be ornamented in any desirable manner or shape.

I do not broadly claim a hair-pin in which the two prongs of the pin are passed through perforations in the lower or bottom part of the head, as such, I am aware, is not new.

I claim—

The herein-described hair-pin, consisting of the bent pin, lower disk, *b*, through which the prongs of the pin pass, and the filling-block *e*, between the bend of the pin and the lower disk, combined with a cap, *f*, closed onto the lower disk and onto the bend of the pin, substantially as described.

JOSEPH R. SMITH.
